UNITED STATES PATENT OFFICE.

PAUL MARIX, OF PARIS, FRANCE.

INDICATING AND REGISTERING APPARATUS FOR METERS.

SPECIFICATION forming part of Letters Patent No. 558,736, dated April 21, 1896.

Application filed December 27, 1895. Serial No. 573,518. (No model.) Patented in France April 5, 1894, No. 237,555, and May 18, 1894, No. 238,606; in Luxemburg October 13, 1894, No. 2,142; in Belgium October 15, 1894, No. 112,250; in England October 20, 1894, No. 20,046; in Spain October 20, 1894, No. 37,473, and in Austria December 8, 1894, No. 44/6,322.

To all whom it may concern:

Be it known that I, PAUL MARIX, of Paris, in the Republic of France, have invented a new and useful Improvement in Indicating and Registering Apparatus for Meters, which is fully set forth in the following specification, and for which I have obtained foreign patents as follows: in France, No. 237,555, dated April 5, 1894, and No. 238,606, dated May 18, 5 1894; in England, No. 20,046, dated October 20, 1894; in Belgium, No. 112,250, dated October 15, 1894; in Luxemburg, No. 2,142, dated October 13, 1894; in Spain, No. 37,473, dated October 20, 1894, and in Austria, No. 10 44/6,322, dated December 8, 1894.

This invention has reference to indicating and registering apparatus for meters, &c.

Counting apparatus or meters of all kinds—such, for instance, as instruments for measuring time, (clocks, watches, &c.,) meters for measuring volume, (such as water, gas, and the like meters,) machines for counting revolutions and the like—as well as registering apparatus of all kinds are designed to effect 25 measurements of continuous working over indefinite periods. For instance, the watch indicates the continuous passage of hours, minutes, and seconds. The gas-meter shows in the same way the continuous passage of 30 cubic feet of gas—that is to say, the volume passed from the moment it is started to work up to the moment at which it is inspected. When it is desired to determine the amount of the operations during a given phase or period, the operator notes down the amount indicated by the meter at the commencement and at the end of the phase or period, or of 35 the operation which it is desired to measure, and the desired result is obtained by means 40 of subtraction. Now that mechanical action is replacing more and more individual labor, it would appear desirable to obtain this estimation of the amount automatically by mechanical means. The chronograph follows 45 out this idea to a certain extent, since it indicates mechanically the commencement and the end of given phases or periods; but such indications cannot be obtained automatically because the actions of stopping, of returning 50 to zero, and of again starting the machine

are dependent on only one driving mechanism. My researches have led me to recognize that the automatic indicating aforesaid cannot be conveniently obtained if the stopping, returning to zero, and restarting of the machine necessary for taking an indication and the measurement of any operation whatsoever be effected by more than two distinct mechanisms. To carry out this system, ordinary measuring devices are specially changed 55 into block indicators or registers, so that a reading of the indication, or of the registering of the measurement of partial operations from the commencement, can be automatically obtained. Owing to the similarity of the 60 present system with the railway “block system” this system may be called the “block-control” system. The block indicator-registers consist of measuring instruments or apparatus—such as watches, clocks, gas and 65 water meters, &c.—controlled by two distinct mechanisms hereinafter referred to as Nos. 1 and 2, as will now be described.

The mechanism No. 2 (which checks or controls the working) has for its object to automatically indicate or register by means of a marker partial operations, while at the same time fixing the commencement of recording by bringing into action an arrangement and recording this commencement on a dial or 70 the like or by returning to the commencement or zero of the scale the indicating parts, so as to allow of each partial operation being 75 read afresh, whether in course of work or by unblocking simultaneously the working of 80 mechanism No. 1, if it has been previously 85 blocked.

The mechanism No. 1 (stop mechanism) has for its object to automatically supply an indication or registration of the end of a partial operation by setting in action an arrangement which checks or stops the movement of the meters and registering apparatus, the work of which is thus rendered intermittent.

By way of example there will be taken a 95 time block indicator-register having its own movement, said indicator-register having for its object to give a determination or account of the “time” which has expired during operations of variable duration. This appara- 100

tus is made by changing a timepiece (such as a watch, clock, &c.) into a block indicator-register.

Referring to the accompanying drawings, forming part of this specification, Figure 1 is an elevation of a clock mechanism, the casing having been removed, to which my invention has been applied, the parts being in a locked position. Fig. 2 is a similar view showing the parts unlocked. Fig. 3 is a top plan view of Fig. 1. Fig. 3^a is a detail. Fig. 4 is a rear elevation of Fig. 1 on a smaller scale, and Fig. 5 is a perspective view of the device shown in the complete instrument. Fig. 6 is an elevation, the outer casing being removed, of an electromagnetic driving mechanism to which my invention is applied. Fig. 7 is a rear elevation of the device shown in Fig. 6. Fig. 8 is an edge view showing the devices for indicating the operation on the chart or diagram-paper. Fig. 9 is a front elevation of the complete instrument, and Fig. 10 is a detail.

The apparatus illustrated in Figs. 1 to 5, inclusive, will first be described.

The motor-movement is similar to that of a timepiece with a balance movement, (such as is used for ship-clocks.) On the minute-arbor is frictionally mounted a minute-hand made in one piece with a cam *a*, of a heart shape, and with a disk *b*, having a pin *c*. The hour-hand is replaced by a disk *d*, Fig. 5, the circumference of which carries the hours, and said disk is frictionally fixed on an arbor *e*, connected to the minute-arbor by a train of wheels, and is provided with a jumper mechanism which causes it to advance a twenty-fourth of a rotation at each complete turn of the minute-hand—that is to say, at every 40 hour.

The disk *d* is divided into twenty-four hours, and can make only one rotation every twenty-four hours. An aperture arranged in the dial-plate in front of the disk *d* exposes 45 the hours indicated on this disk one by one as the disk rotates.

The jumper mechanism is constructed in the following manner: A lever *f*, pivoted at *f'*, is engaged by a spring *f''*, which constantly 50 presses it from right to left. Said lever has at its free end a nose, which constantly lies in the path of the pin *c*. A lever *g* is pivoted on the lever *f* and carries on one of its extremities a weight *g'*, forming a counterweight, 55 which tends to constantly raise the other extremity, which is slightly hooked or forked. A wheel *h*, provided with twenty-four pins projecting laterally from its rim, is fitted on the arbor *e*, and the forked end of the lever *g* bears 60 upwardly against these pins. A heart-shaped cam *i* is mounted on the arbor *e* and is only movable with the disk *d*. At each rotation of the minute-hand the pin *c* of the disk *b* will encounter the nose of the lever *f*, forcing the 65 latter back against the action of the spring *f''*, and the lever *g*, carried by the lever *f*, will thus slip under the pins of the wheel *h*, passing

from pin to pin and engaging behind each owing to the action of the counterweight *g'*.

Each time the lever *f* escapes from the pin 70 *c* it returns sharply to its normal position under the action of the spring *f''*. In this return movement said lever draws the lever *g* with it, thus causing the latter to sharply push the pin-wheel *h*, and thus advance said wheel 75 one twenty-fourth of a rotation, thereby advancing the hour-disk to the same extent.

In order to control the movement of the pin-wheel *h*, and consequently of the disk *d*, so that the numbers may be visible always at 80 the center of the aperture in the dial-plate, a stop-catch is combined with the pin-wheel *h*, which catch is formed of a lever *h'*, carrying at one end a small roller, which lever, under the action of a spring *h''*, always presses its 85 roller against and between two pins of the pin-wheel.

The mechanisms Nos. 1 and 2 act in the following manner: A lever *j*, pivoted at *j'*, has its upper end terminated by an arm *k*, which lies 90 below the button *A* of the mechanism 1, and said lever *j* has another arm, which carries a small roller *k'*. A spindle *l*, arranged on the lever *j*, passes through an opening in the plate which carries the whole mechanism and is provided at its end with a flexible arm *l'*, the end of which lies a little above the balance *m* of the clock-movement. A spring *n*, furnished with a V-shaped tooth *n'*, presses said tooth on the spindle *l*. A pivoted lever *o*, held up 100 by a spring *r* and situated in the plane of the lever *j*, carries at its free end a roller *o'*, riding on the cam *a*. Said lever *o* also carries a second roller *o''*, riding on the cam *i*. A tooth *p* is formed on the lever *o* and lies in the plane 105 of the roller *k'* of the lever *j*. A lever *q*, carrying at its end a roller *q'*, bears with said roller on the lever *o*. The button *M* of mechanism No. 2 acts directly on the lever *q*. Behind the second plate of the frame is a disk *S*, on 110 which is placed a card to receive the registering-diagram. This disk *S* is operated directly from the barrel of the motor-train by means of an intermediate wheel *S'*. This disk makes one rotation every twenty-four hours. Fixed 115 on the pivot-spindle of the lever *o*, which passes through the two plates of the frame, is a marker *t* for tracing the registering-diagram. This marker moves with the lever *o*. A barrel 120 operates the clockwork in the ordinary manner, the minute mechanism moving the minute-hand, and the hours being indicated, as before described, by a disk turning intermittently and presenting the hours successively at the aperture in the dial-plate. The disk 125 is operated in the manner described above.

When the button *A* is pressed by hand, the entire movement of the apparatus is locked, as shown in Fig. 1. When the button *M* is pressed by hand, the movement is unlocked, 130 as shown in Fig. 2, and consequently the apparatus is set going, and at the same time, as will be hereinafter explained, the indicating parts (being the minute-finger and the hour-

disk) are returned to the zero or commencement of the scales and a short mark is made on the diagram-card independent of the normal indicating-line registered, and said short mark indicates the commencement of registering a fresh period of work. The above motions are effected as follows: When the button A of mechanism No. 1 is pushed down by hand, the arm *k* is depressed, causing the lever *j* to swing on its pivot *j'*. In its movement the lever *j* draws with it the shaft *l* and the flexible strip *l'*. This latter then exerts an oblique pressure on the balance *m* of the clock-movement, and thus locks the movement. During its movement the shaft *l* has passed from right to the left of the V-shaped tooth *n'*, causing the spring *n* to spring up and down again. The shaft *l* and the strip *l'* are therefore retained in their former position by the tooth *n'*, which now lies to the right of the shaft. On the strip *l'* being withdrawn from the balance this balance will easily rebound and again resume its motion. It need not therefore be feared that the clock-movement will remain stopped after the unlocking of the balance, as would have taken place if the pressure were simply vertical instead of oblique.

The mechanism No. 2 causes the apparatus to resume work with a return of the hour-disk and minute-hand to the commencement or zero of the scales. For this purpose the button M is depressed by hand, and thereby pushes the lever *q* downward, so that the roller *q'* bears on the lever *o*, which latter is also pushed downward. The lever *o* in its descent returns the lever *j* to its first position. In fact, the tooth *p* on the lever *o* in its descent encounters the roller *k'*, carried on an arm of the lever *j*, and, owing to the inclined shape of said tooth, returns the lever *j*, and therewith the flexible strip *l'*, carried on the spindle *l*, which latter passes to the right side of the V-shaped tooth *n'*, the spring *n* yielding to allow the spindle *l* to pass the tooth. Thus the clock-movement is unlocked and the whole again set to work. Simultaneously with the above movements the two rollers *o' o''* exert pressure on the two heart-shaped cams *a* and *i*, respectively, and cause them to turn until said rollers sit on the deep part of the cams. The minute-hand and the hour-disk operated by said cams are thus returned to zero or the commencement of the scales. At the same time the marker or pencil *t*, which moves with the pivot-spindle of the lever *o*, is lowered and marks on the diagram-card a line indicating the commencement of registering a fresh period of work.

As soon as the mechanism No. 2 is returned by releasing the button M the heart-cams are liberated by the spring *r*, which returns the lever *o* to its first position. The marker or pencil *t* is drawn upward simultaneously to the position of the normal registering-line on the diagram-card.

In the above example the two mechanisms

Nos. 1 and 2 are entirely distinct and are controlled directly by operating by hand either one or other of the push-buttons. They may, however, be controlled by the intermediation of a lever and chain, if such be deemed necessary, to facilitate the work for which the apparatus is intended, or the mechanisms may be controlled from a distance by combining them with the armature of electromagnets.

In the aforesaid example the diagram is represented by a simple disk, on which a pencil traces the record; but a cylindrical surface may be employed, on which graduated diagrams may be arranged, whereon the pencil or marker *t* will record the operations in a similar manner.

In order that the record may be traced to a larger scale to facilitate the reading, two connected cylinders may be employed, on which the diagram-band is wound in the same way as a driving-belt, thus obtaining a greater extent of recording-surface. There would then be larger scales on which the marking-pencil would be readily visible. Finally, if it be desired not to change the diagram too frequently, the diagram-paper could be extended and wound on rollers in an analogous manner to that of the Morse telegraph apparatus.

The time block indicator-register which has been described above may, instead of being actuated by a winding-up mechanism, receive its motion by means of electricity from a clock placed at a distance, like the known system of electric clocks.

As a second example, a description will now be given of a block indicator-register actuated by an electrical receiver instead of having its own motor-movement and controlled by the two mechanisms, as before explained. This apparatus is composed, essentially, as in the first instance, of indicating and registering parts actuated by an ordinary minute-wheel having a suitable movement, which engages and disengages with the meter-wheels. The parts are set to the commencement or zero of the scale, and the start is marked on the diagram-card, as in the previous example, by the action of the mechanism No. 2, which at the same time sets the apparatus in operation. The stoppage is effected by mechanism No. 1, with, however, the simple difference that instead of locking and unlocking of the movement the parts are in this instance engaged and disengaged with the principal movement, (as by breaking the electrical circuit.)

Referring to Figs. 6 to 10, the units or minute hand (supposing we are considering a timepiece) is situated on the arbor of the clockwork in the ordinary manner, which need not be described here. The hour-hand moves over a small dial on the larger one and is fixed on an arbor *e*, actuated by a jumper mechanism which causes it to advance a cog at each complete rotation of the minute-finger. This jumper movement, the mechanism of which it is not intended to claim, is

analogous to that described in the before-described example and is shown on the drawings; but a description of it is not given here for the sake of brevity. The two fingers are 5 each connected with a heart-shaped cam *a* and *i*, which move with them. The mechanism No. 2 is formed of a push-rod *M*, which bears against a lever *o*, which a spring *r* tends to constantly raise. This lever carries three 10 rollers *o'*, *o''*, and *p*³, of which the two rollers *o'* and *o''* lie in the plane of the two cams *a* and *i* and exert a pressure on said cams when the lever *o* is depressed by the push-rod *M*. This pressure has for its object to impart to 15 the two cams *a* and *i* a rotation until the two rollers *o'* and *o''* have moved to the deepest part of the two cams. This rotation of the cams is transmitted to the hands, which are thus brought to the zero or commencement 20 of the scales. At the same time the roller *p*³ encounters the lug *k*³ of the electrical disengaging stop-lever *j*, as will be seen later on, and this roller coming in contact with the lug *k* has for its object to push the lever *j* back- 25 ward and to thus close an electric circuit.

The way in which the stoppage is produced by the mechanism No. 1 will now be described. The lever *j* ends in a nose of a special form, against which the push-rod *A* bears, and carries, moreover, a spindle *l*, passing through the movement frame-plate, under which pin is depressed a V-shaped tooth *n'*, carried by a spring *n*, which tooth engages the spindle *l*. On the nose of the lever *j* is fixed a curved 30 piece *m*³, which passes behind the plate and carries a contact *m'*, adapted to bear on a binding-screw *m''* of an electric circuit, the current of which actuates the electromagnet of the receiver. This screw *m''* is perfectly 35 insulated electrically, and a current consequently can only traverse the magnet when the contact-piece *m'* bears against it. When the position of the lever *j* is such that the spindle *l* is situated to the right of the V-shaped 40 tooth *n'*, contact takes place and the apparatus is in operation; but if by pressure on the button *A* the lever *j* swings so as to carry the spindle *l* to the left of the V-shaped hook *n'* the contact *m'* of the curved piece *m*³ is removed 45 from the screw *m''*, and the electric circuit being thus broken the receiver is disengaged from the meter, which imparts its impulse to it. The apparatus is thus stopped. When, 50 however, the roller *p*³ of the lever *o* turns the lever *j* to its first position, as hereinbefore explained, the contact is re-established, and thereby the indicating devices are returned to the commencement or zero of the scales and the apparatus simultaneously set to work.

55 The recorded diagram is obtained in the same manner as in the previously-described example, there being in the present instance on the same arbor as that of the units-hand a cylinder *s*, on the surface of which the paper marked with the scales or graduations is suitably arranged. It is on this paper that the

diagram is registered. The pencil or marker *t* bears against said cylinder and may be moved at right angles to the direction of rotation of the cylinder. For this purpose the 70 pencil or marker *t* is pivoted at *t'* on a bracket fixed to the frame-plate. A spring *w* retains the pencil-holder against a rod *u*, which slides through a perforation or socket *u'* in the plate *U* and carries a little roller *u''*, with which engages a cam *v*, formed on the lever *o*. A hole is made in the second plate *U*² to allow free passage to the roller *u''*. Under these conditions each time the button *M* is operated the lever *o* is depressed, the cam *v* moves past 80 the roller *u''*, and the pencil is drawn to the left by the spring *w* drawing the rod *u* against the cam-face, and a short line is thus traced on the diagram, thus indicating the commencement of a partial operation. As soon as the 85 button *M* is released the lever *o*, under the action of the spring *r*, returns to its normal position and the pencil is consequently pushed by the cam *v* back to its original position. It must be understood that the diagram can just as well be recorded on a disk as in the first-described example or on a band arranged as in the Morse apparatus, &c.

It is also to be understood that the two mechanisms Nos. 1 and 2 can equally well be 95 controlled from a distance by the push-buttons being operated by electromagnets instead of being operated by hand; finally, that the mechanism for returning to zero by means of heart-shaped cams can be replaced by 100 springs or other arrangements.

The minute mechanism of the block indicator-register, instead of being operated or stopped and started by a force such as electricity, water, &c., may be simply operated 105 by a transmitting mechanism having meter-wheels with a continuous movement, and engagement and disengagement being made by means of a transmitting mechanism, for example, or by geared wheels if the distance 110 which separates the lever indicator-register from the meter be not too great.

The apparatus just described, in place of acting as a time block indicator, can act as a 115 kilometric or volumetric (for gas, water, &c.,) block indicator-register, it being sufficient that the contacts which drive the indicating parts be replaced by the wheels of a gas-meter, &c.

To sum up in a general manner, the mechanism No. 1 checks or stops the movements either by locking the parts, as in the first-described example, or by disengaging the parts, as in the second example. The mechanism No. 2 sets the parts in motion and simultaneously draws to zero or commencement of the scale the hands (if they are movable) or the dial (if this is movable) and marks on the diagram card or band a mark indicating the start. The function of the mechanism No. 2 125 is to return the indicating organs to zero and to produce a starting-mark on the diagram

while the apparatus is working, (the movement not having been stopped by mechanism No. 1,) and that in such a manner that the drawing to zero or the indication of the start 5 can never be effected by the mechanism No. 2 without the indicating parts or the diagrams continuing or taking up, at the same stroke, their work to start from the zero of the scales and from the said indicating - mark of the 10 start. The returning to zero can be effected by the action of a lever on cams, as has been hereinbefore described, or by barrels adapted to draw backward the fingers or the dials, or in any other usual method. The two mechanisms 15 Nos. 1 and 2 can be arranged on any measuring or counting apparatus, which will then come under the category of block indicating-registers described in the first example, or they may be arranged on supplementary apparatus without their own movement, as described in the second example. In all 20 these cases it will be understood that as mechanisms Nos. 1 and 2 have inverse actions it may be advantageous or desirable in 25 certain cases that the operating of the two mechanisms should be compulsorily alternative. Nothing could be more simple than the 30 working of this apparatus on the principle of the block system of railways, where the operating of one mechanism can only be effected by operating another mechanism to unlock the first.

The mechanisms Nos. 1 and 2 could be also 35 connected to bells or with separate registering apparatus, so as to obtain results or means of control at a distance, which bells or registering apparatus thus work in unison with the mechanisms Nos. 1 and 2 automatically at the commencement and at the end of the 40 controlled operations. The mechanisms Nos. 1 and 2 could, besides blocking the measurement of the operation, simultaneously block the operation itself—that is to say, control the block indicator-register and the operations 45 of which the measurement is being taken.

By way of example, the block indicator-register could be used with telephones to determine the duration of the conversation, and 50 the mechanisms Nos. 1 and 2 besides controlling the block indicator-register could simultaneously therewith open and close the telephone-circuit.

Similarly, in the application to cabs for the 55 purpose of ascertaining the duration of the hiring period, the mechanisms Nos. 1 and 2 could at the same time operate disks to indicate that the cab is engaged or for hire.

The mechanisms Nos. 1 and 2 can finally 60 be controlled either manually by handles, levers, chains, &c., or from a distance by electromagnets. It is evident that when simply indication or registration alone is required for the purpose in view parts of the block 65 indicator-register may be omitted—that is, either the registration parts or, on the contrary, the indicating parts—in such manner

as to reduce the apparatus to either a simple block indicator or to a simple block register.

Having thus described my invention, what 70 I claim as new, and desire to secure by Letters Patent, is—

1. In an indicating and registering apparatus, the combination with an indicator—such as a dial and a hand—driven from an 75 apparatus—such as a meter &c.—for indicating the duration of an operation or partial operation thereof, and a diagram card or chart upon which the duration of successive intermittent or partial operations is recorded, of 80 two distinct mechanisms, one for arresting the indicator at any stage of the operation, and the other for returning the indicator to zero and for starting the same and simultaneously recording upon the card or chart the beginning 85 of a new phase of the operation, substantially as described.

2. In an indicating and registering apparatus the combination with an indicator device—such as a dial and a hand—driven from 90 an apparatus—such as a meter &c.—for indicating the duration of an operation or partial operation of said apparatus, a diagram card or chart for receiving a record of the duration of successive intermittent or partial operations 95 of the apparatus, of two distinct mechanisms one for arresting and locking the indicating device at any stage of the operation, and the other for recording upon the chart or diagram the total period of operation, for operating upon the first mechanism to unlock 100 the indicating device, returning the same to zero, and simultaneously recording upon the chart the beginning of a new phase of the operation, and for indicating at any time during 105 the operation the extent of a portion thereof, substantially as described.

3. The combination with a minute-hand of a suitably-operated clock mechanism and an hour-indicating device driven therefrom, of a 110 diagram card or chart moved by said clock mechanism upon which successive intermittent or partial operations are graphically recorded, a lever for arresting the movement of and locking the clock mechanism, an arbor 115 carrying a marker making contact with the diagram card or chart, a second lever mounted on said arbor, means for moving the first lever to arrest and lock the clock mechanism, and means for actuating the second lever to 120 unlock and start said mechanism, for returning the minute and hour devices to zero, and for operating the marker to indicate upon the chart the ending of one and the beginning of another intermittent operation or partial operation, 125 substantially as described.

4. The combination with a minute-hand of a suitably-operated clock mechanism, and an hour-indicating device driven therefrom, of a diagram card or chart moved by said clock 130 mechanism and upon which successive intermittent operations or partial operations are recorded, a lever actuated by a key for arresting and locking the clock mechanism—as by

engagement with the fly-wheel—an arbor carrying a marker making contact with the diagram card or chart, a second lever on said arbor, projections or arms on said lever for engaging the first lever to return the same to its normal position and to unlock and start the clock mechanism, and for engaging heart-shaped cams on the minute and hour mechanisms to return the same to their zero positions when the second lever is actuated, and

a key for actuating said lever, substantially as described.

In testimony whereof I have signed this specification in the presence of two subscribing witnesses.

PAUL MARIX.
